UNITED STATES PATENT OFFICE.

ERNEST O. HOWLE, OF CHICAGO, ILLINOIS, ASSIGNOR TO MID-WEST INCINERATOR CORPORATION, OF CHICAGO, ILLINOIS, A CORPORATION OF ILLINOIS.

INCINERATOR DOOR.

Application filed November 10, 1927. Serial No. 232,415.

This invention relates to certain improvements in incinerator doors, particularly to an improved door for closing the opening in an apartment leading to a chute-fed incinerator.

The principal object of this invention is to provide an incinerator door, a door frame, and a supporting casing which is imbedded in the building wall, these members being provided with integral parts adapted to cooperatively engage whereby the door will be pivotally mounted on the frame, and the frame secured to the casing, so that substantially all of these connections will be hidden when the parts are assembled and the door is closed, and the door and frame will present only smooth exposed portions which may be completely covered with a vitreous enamel, or other suitable coating to harmonize with the wall decorations and present an attractive and ornamental appearance.

The above, and other objects and advantages of this invention will be more apparent from the following detailed description of one approved form of assembly, embodying the principles of this invention.

In the accompanying drawings:

Fig. 1 is a vertical section through a portion of a building, partially broken away, illustrating the use of these doors or closures in an incinerator chute.

Fig. 2 is an enlarged vertical section through the assembled members of the closure with the door in closed position.

Fig. 3 is a perspective view of the casing member (on a somewhat smaller scale).

Fig. 4 is a rear elevation of the door.

Fig. 5 is a rear elevation of the door frame, showing the door engaged therewith and partially opened.

Fig. 6 is a perspective view of a portion of the front of the door and frame when assembled, with the door closed.

The incinerator (the upper entrance to which is indicated at 1) is located in the basement of the building. A chute 2 leading down through the building permits the dumping of materials from each floor into the incinerator. The upper end of this chute communicates with a suitable flue or chimney. A separate back-flue 3 provides a separate free passage for smoke and gases, and eliminates any choking or back-firing due to the possible obstruction of the inner flue or chute 2.

At a suitable position in a side wall of each floor of the building an entrance passage is provided to give access to the chute 2, and the present invention is concerned particularly with improvements in the frame and closure for this entrance opening. A metallic frame or casing 4 (shown in perspective in Fig. 3), usually made of cast iron, is embedded or built into the side wall of the building. This frame is open at its front and rear and serves as a lining for the wall opening, and also as a support for the door and door frame hereinafter described. Casing 4 preferably comprises vertical side walls 5 and 6, a horizontal top wall 7, and a downwardly and inwardly sloping bottom wall 8. An integral bracket 9 formed on the bottom wall 8 serves as a means for supporting and anchoring the casing within the wall 10 of the building. When in position, the front face 11 of casing 4 serves as a frame for the inlet opening, and will be substantially flush with the exposed surface of wall 10. The lower front edge 12 of the face 11 of the casing (that is the upper front edge of the lower wall 8), is provided with a pair of forwardly projecting lugs or fingers 13, one adjacent each lower corner of the casing. As will hereafter be apparent, these fingers might be connected together in the form of a single forwardly projecting rib or flange, but it is convenient to remove the central portion of this rib, thus saving weight and material.

The door frame 14 is in the form of a rectangular member with a similarly shaped central opening, the rear faces of the top bar 15 and side bars 16 and 17 being adapted to fit snugly against the corresponding portions of the face 11 of casing 4. The upper rear edge of the lower cross bar 18 is provided with a rearwardly and downwardly projecting flange 19 adapted to hook over and fit snugly against the upper edge of the downwardly inclined bottom wall 8 of casing 4. This hooked engagement serves to hold the bottom of the door frame 14 in place, and its upper corners are provided with screw or bolt holes 20 adapted to register with similar openings 21 in the casing 4, thus holding the two members rigidly together. The front face of the frame 14 is recessed as indicated at 22 to house the pivoted door 23, so that when the door is closed the front faces of the door and frame 110

will be substantially flush with one another. When the door 23 is closed it covers the fastening means which have been passed through holes 20, so that there are no visible means by which the frame 14 is attached to the wall. The lower portion of the transverse bar 18 of the frame, below the inwardly projecting flange 19, is formed with a transverse groove or channel 24 which

10 opens rearwardly, and the ends of this channeled portion 24 terminate short of the sides of the frame so as to leave open notches 25 between the ends of this channeled portion and the side ribs 26 of the frame. These 15 notches 25 are open at the front, rear and bottom of the frame, but closed at the top.

The one-piece metal door may have a substantially smooth and unbroken front surface, although it is here shown as formed 20 with a slightly depressed central panel 27, merely for ornamental purposes. On its rear face the door is formed with a rearwardly projecting side rib 28 extending around the four sides of the door and 25 adapted to fit snugly against the recessed surface 22 of the door frame 14. The door is also formed with a pair of vertical rearwardly projecting flanges 29 near its side edges, to which the hopper 30, hereinafter 30 described, is attached. At its lower corners the door is formed with a pair of downwardly projecting, substantially cylindrical lugs 31 which are adapted to fit snugly within the notches 25 in the door frame. Hinge 35 pins 32 project inwardly toward one another from these lugs 31. Preferably, these hinge pins are pieces of steel rod which are cast into the lugs 31 when the door is formed. A handle 33 is secured to the upper front 40 portion of door 23 by means of screws 34 passed through the door from the rear and engaging with the posts of the handle.

To assemble this device, the lugs 31 and pivot pins 32 are hooked into the notches 25 and channel 24 of frame 14, from the bottom and rear and then the door is swung up into closed position. This assembly is then engaged with the casing 4 by hooking the lip or flange 19 on frame 14 over the 50 upper edge of the bottom wall of the casing, and then inserting the screws or other fastening devices through the mating holes 20 and 21 in the door frame and casing. The lugs or fingers 13 will automatically be 55 projected into the channel 24 against the rear or exposed sides of the pivot pins 32 so as to prevent these pins from slipping rearwardly. It will be noted that the pivot pins are now confined on all sides so that 60 the door 23 may be swung about these pins as a pivotal axis. When the door is in its closed position, it will incline slightly inwardly (see Fig. 2) at its upper end so as to be held in this closed position by its own 65 weight. The weight of the hopper 30,

which is secured to the flanges 29 on the rear of the door, also tends to hold the door closed. When the door is swung to the open position as shown in dotted lines at the top of Fig. 1, the garbage or other refuse may be placed in the hopper 30 and when the door is swung to closed position, this material will automatically be dumped into the chute 2.

It will be noted that the only accessible 70 fastening devices are the screws by which the upper end of frame 14 is secured to the casing, and these screws are covered by the door when this is in closed position. There are no exposed hinge pins or fasteners of 80 any kind at the lower pivoted edge of the door, and the entire exposed edges and sides of the door frame as well as the door are smooth and substantially flush with one another. This permits these surfaces to be 85 continuously coated with a heat-resisting vitreous enamel, which is preferably selected to match the other interior decorations of the room, and there are practically no exposed rough edges or openings to cause this 90 enamel to crack off or become disfigured.

I claim:

1. A closure for incinerator chutes comprising in combination: a hollow casing open at opposite ends; a door frame; a door; and means on the casing and on the inner side of the door frame at one edge thereof for engaging the frame with the casing; devices at another edge of the door frame and covered by the door when closed, 100 for securing this edge of the frame to the casing; and elements for hinging the door to the frame arranged on the inner sides of the door and frame so as to be concealed when the door is closed.

2. A closure for incinerator chutes comprising a metallic casing to be placed in the building wall as a lining for the receiving opening, a door frame, a door, there being cooperating hinge portions integral 110 with the door and frame for pivotally mounting the door in the frame, and means integral with the casing projecting into engagement with these hinge members to hold the hinge members in assembled relation 115 and prevent disengagement thereof when the frame is mounted on the casing.

3. A closure for incinerator chutes comprising a metallic casing to be placed in the building wall as a lining for the receiving opening, a door frame, a door, there being integral hinge pins formed on the door, an integral channel formed on the rear of the frame for receiving and concealing the hinge pins, and means integral 120 with the casing for holding the pins in place within the channel when the parts are assembled.

4. A closure for incinerator chutes comprising an open ended metallic casing to be 130

placed in the building wall as a lining for the receiving opening, the outer open end of this casing serving as a frame for the inlet opening, and the lower wall of the casing sloping inwardly and downwardly, this lower wall being formed with outwardly projecting fingers, a door frame formed along its lower rear face with a downwardly and inwardly projecting flange adapted 10 to be hooked over the similarly inclined bottom wall of the casing, a door, there being cooperating integral hinge members formed on the door and frame for pivotally mounting the door on the frame, the 15 hinge members being concealed when the parts are assembled, the fingers on the casing cooperating with the hinge members to hold them in engaged relation.

5. A closure for incinerator chutes comprising an open ended metallic casing to be placed in the building wall as a lining for the receiving opening, the outer open end of this casing serving as a frame for the inlet opening, and the lower wall 20 of the casing sloping inwardly and downwardly, this lower wall being formed with outwardly projecting fingers, a door frame formed along its lower rear face with a downwardly and inwardly projecting flange adapted to be hooked over the similarly inclined bottom wall of the casing, and also formed with an inwardly opening channel portion 25 the ends of which terminate short of the 30 sides of the frame so as to leave downwardly opening notches, and a door formed at its lower corners with downwardly projecting hinge lugs adapted to fit within the notches in the frame, and hinge pins projecting from the lugs and adapted to be received in the channel of the frame, the fingers on the casing projecting into the channel to engage and hold the pins within the channel.

nate short of the sides of the frame so as to leave downwardly opening notches, and 35 a door formed at its lower corners with projecting portions adapted to pivotally engage within the notches and channel, the fingers on the casing serving to hold these pivotally connected parts against disengagement.

6. A closure for incinerator chutes comprising an open ended metallic casing to be placed in the building wall as a lining for the receiving opening, the outer open 45 end of this casing serving as a frame for the inlet opening, and the lower wall of the casing sloping inwardly and downwardly, this lower wall being formed with outwardly projecting fingers, a door frame formed 50 along its lower rear face with a downwardly and inwardly projecting flange adapted to be hooked over the similarly inclined bottom wall of the casing, and also formed with an inwardly opening channel portion 55 the ends of which terminate short of the sides of the frame so as to leave downwardly opening notches, and a door formed at its lower corners with downwardly projecting hinge lugs adapted to fit within the notches in the frame, and hinge pins projecting from the lugs and adapted to be received in the channel of the frame, the fingers on the casing projecting into the channel to engage and hold the pins within the channel.

ERNEST O. HOWLE.
